UNITED STATES PATENT OFFICE.

CHARLES H. POPE, OF BROCKTON, MASSACHUSETTS.

DOOR.

SPECIFICATION forming part of Letters Patent No. 693,440, dated February 18, 1902.

Application filed May 2, 1900. Serial No. 15,189. (No model.)

To all whom it may concern:

Be it known that I, CHARLES H. POPE, of Brockton, county of Plymouth, State of Massachusetts, have invented an Improvement in 5 Doors, of which the following description, in connection with the accompanying drawings, is a specification, like numerals on the drawings representing like parts.

This invention relates to doors; and the object of the invention is to provide an improved device of this character so constructed that the employment of a threshold upon its frame or the floor in proximity thereto is not necessary.

15 The invention includes as one of its features a door and its frame, the door having a bar or strip, means to hold the bar or strip above the lower edge of said door when the same is open, and means usually mounted upon the 20 frame to throw and maintain the bar or strip down below the lower edge of the door when the same is closed. In the present case the door has in its lower edge a longitudinal groove adapted to snugly receive a bar or 25 strip, and I prefer to employ a spring to hold said bar or strip in the groove when the door is open, and said bar or strip may be engaged by a projection or stud disposed in the path of the same upon the frame to force the same 30 down against the sill or carpeting or other covering thereon. By this construction I am enabled to dispense with the usual threshold, while the bar or strip carried by the door serves when down and while the door is shut 35 to close the opening between the door and floor and exclude cold.

The invention is shown in one convenient embodiment thereof in the accompanying drawings, wherein—

40 Figure 1 is a front view of a portion of a building having a frame inclosing a door including my improvements. Fig. 2 is a sectional view of a portion of the door and frame. Figs. 3 and 4 are transverse sections taken in 45 the lines 3 3 and 4 4, respectively, Fig. 2.

Referring to Fig. 1, the numeral 5 indicates a door-frame, in which a door, as 6, is hinged. The door does not extend completely to the floor 7; but the space between the two parts 50 when the door is shut is closed by a strip or bar which serves to exclude cold from the interior of an apartment furnished with the

door and which strip when the door is open may be seated in a channel or groove in the lower edge of the door.

55

The door 6 has at its lower end the cross-piece 8, constituting, in effect, a continuation thereof, and which is grooved or channeled, as at 9, transversely of the door and completely across the same, the channel being 60 semicircular in cross-section and being adapted to receive the correspondingly-shaped strip or bar 10, which when the door is open is seated in the channel, as indicated by the dotted lines in Fig. 4, but which when the door is 65 shut is adapted to rest against the floor 7 or the covering thereof, as clearly shown in Fig. 4. The strip 10 is preferably hinged to the door to swing down and up, as the case may be, the hinges being denoted by 12 and 13 70 (see Fig. 1) and both of them being countersunk in place. The bar 10 is held positively within the channel 9, and to effect this result I have illustrated a coiled spring, as 14, surrounding the pintle 15 of the hinge 13 and connected, respectively, with the two members of 75 said hinge.

The frame 5 in the present instance is provided with means of a suitable nature to engage the swinging strip 10 when the door is 80 nearly shut, so that on a slight further movement the said strip will be swung down with its free edge in contact with the floor 7 or its covering. I have shown a roller 16 as a convenient device to engage the strip 10, the 85 roller being supported by the stud or screw 17, extending through a longitudinal slot 18 in a disk or plate 19, set into one of the stiles of the door-frame. A recess, as 20, is located back of the disk 19 and receives a nut 21, into 90 which the threaded end of the stud or screw 17 is tapped. By turning the stud or screw 17 the same can be raised or lowered for the purpose of adjusting the roller, and when properly positioned the said screw will be 95 turned in the opposite direction to firmly hold the same in the desired position. By making the screw 17 adjustable vertically the roller thereon may be so adjusted as to swing the strip 10 down different distances, according 100 to the thickness of the rug or carpet used on the floor, so that the opening between the door and the floor may always be closed when the door is shut. The door is cut away at its

lower corner, as at 22, so that the roller 16 can engage the adjacent end of the strip 10 in order to swing the same down. As soon as the door is opened and the strip 10 is carried out 5 of contact with the roller 16 the strip will be swung up into the channel 9, into the dotted-line position, by the power of the spring 14 and will be there held until the door is shut.

The invention may be modified within the 10 scope of the accompanying claims.

Having described my invention, what I claim, and desire to secure by Letters Patent, is—

1. A door having a groove curvilinear in 15 cross-section in its lower edge, a strip fitted to said groove, the inner edge of the strip having a pivotal connection with the door, means to normally hold said strip in place in the groove, one corner of the door being cut

away above the strip, a projection on the 20 door-frame adapted to enter said cut-away portion as the door is closed and contacting with the upper side of the strip to thereby depress the same.

2. A door and its frame, the door having a 25 bar or strip, means to hold the bar or strip above the lower edge of said door when the same is open, a screw provided with a roll to engage said bar or strip, a plate longitudinally slotted to receive said screw, and a nut 30 engaged by the screw.

In testimony whereof I have signed my name to this specification in the presence of two subscribing witnesses.

CHARLES H. POPE.
